United States Patent Office.

P. D. BECKWITH, OF DOWAGIAC, MICHIGAN.

Design No. 3,784, dated December 14, 1869.

DESIGN FOR A STOVE.

The Schedule referred to in these Letters Patent and making part of the same.

To all whom it may concern:

Be it known that I, P. D. BECKWITH, of Dowagiac, in the county of Cass, and State of Michigan, have originated and designed a new Stove, of which the following is a full, clear, and exact description, reference being had to the accompanying or drawings, making part of this specification, in which—

Figure 1 is a front elevation of the design.

Figure 2 is a side view of the stove.

Figure 3 is a top view.

Similar letters of reference indicate corresponding parts in the three figures.

The design consists of an upright stove, which, in a horizontal section, taken at any point above its base, D, is of a circular form.

The body of this stove consists of a downwardly-

tapering lower section, C, receiving, upon its upper flaring end, a cylindrical section, B, in the front part of which the door P is seen.

This cylindro-conical body is surmounted by a hemispherical cap, A, from the centre of which rises a cylindrical pipe, a.

The base D, of this stove, may be rectangular or of any other suitable shape, and the door P may be ornamented in any desirable manner.

I claim, as my invention—

The design for a stove, as described and shown.

P. D. BECKWITH.
